JOSEPH MANNIX,
INVENTOR

Victor J. Evans

ATTORNEY

WITNESS:

Gregory Kelly

UNITED STATES PATENT OFFICE.

JOSEPH MANNIX, OF SARANAC LAKE, NEW YORK.

CONCRETE CASKET VAULT.

Application filed April 4, 1922, Serial No. 549,484. Renewed December 14, 1923.

To all whom it may concern:

Be it known that I, JOSEPH MANNIX, a citizen of the United States, residing at Saranac Lake, in the county of Franklin and State 5 of New York, have invented new and useful Improvements in Concrete Casket Vaults, of which the following is a specification.

This invention relates to burial vaults and one of the objects is to produce a device of 10 this nature having a composition which shall be water-proof.

Another object is to produce a device of this nature made in sections and provided with connecting flanges of such shape as to 15 prevent breakage where there is movement of the parts relatively to each other.

Another object is to provide means whereby the various sections may be readily lowered into place and which will also serve as 20 means for elevating the coffin from the lower floor.

Another object is to produce a device of this kind in which any iron utilized in the construction will be so placed as to be prevented from deterioration. 25

Another object of the invention is to provide a device of this nature with sectional overlapping covers whereby the strength of the device is greatly increased.

With these and other objects in view, the invention resides in certain novel construction and combination and arrangement of parts, the essential features of which are hereinafter fully described, are particularly 30 pointed out in the appended claims, and are illustrated in the accompanying drawing, in which:—

Figure 1, is a side elevation of my improved burial vault.

Figure 2, is a top plan view of the same with parts removed.

Figure 3, is a central longitudinal sectional view.

Like characters of reference, refer to like 45 parts in all views.

The present invention contemplates the provision of a burial vault constructed particularly of concrete, and as it is desirable to have these vaults waterproof, I prefer to 50 make the vault herein described of a composition comprising two parts of liquid enamel to every one hundred pounds of cement used in the mixture.

Referring now to the drawing in detail, 10 55 and 11 represent two base members which

are formed with side channels 12 and end channels 13, the same being inclined toward the center so as to tend to throw the walls toward the center and prevent their falling apart. A plurality of lugs or eyes 14 are 60 formed on the floor or secured thereto and these may be utilized for lowering the members 10 and 11 to place in the grave and afterwards will form suitable supports for holding the coffin above the floor of the vault. 65 It will be noticed that the contiguous ends of members 10 and 11 are beveled and lap each other so that by the addition of a little cement, at the time of laying, the same may be firmly secured in place. 70

The upright structure comprises side members 15 and 16 and corner members 17 which extend half way across the end and also at right angles for distances along the respective sides. The various members are provided with round lugs 18 and grooves 19, the purpose of the rounding of these portions is so that a limited amount of relative movement may be indulged without breaking the tenon. If desired, hooked or flanged bars 80 of iron or steel may be provided to cap the structure as shown at 20 and 21.

The top is preferably made of three sections which are numbered 22, 23 and 24, and which are beveled at their contiguous faces. 85 Each of the members 22, 23, and 24, is provided with one or more ribs 25, for strengthening it, and these ribs are preferably provided with apertures 26, whereby they may be readily lowered to place by means of ropes or straps. 90

A cover is provided consisting of three parts, 27, 28 and 29, which overlap the joints between the members 22, 23, and 24, and fit on to the ribs thereof so as to hold the members 22, 23 and 24 against displacement. Members 22, 23 and 24 are also provided with a downward projection which fits inside the walls of the upright portion so as to hold them against slipping. Eyes or rings 30 may 95 be provided in the members 27, 28 and 29, for the purpose of lowering the same to place. 100

While I have described what I deem to be the most desirable embodiment of my invention, it is obvious that many of the details may be varied without in any way departing from the spirit of my invention, and I therefore do not limit myself to the exact 105 details of construction herein set forth nor 110

to anything less than the whole of my invention, limited only by the appended claims.

What is claimed as new is:—

1. A vault of the class described comprising a pair of base members each provided with a groove and with a plurality of eyes on its upper surface, a body structure constructed to fit into said grooves and including a plurality of sections joined by rounded tenons and grooves, a lid comprising a plurality of overlapping sections having ribs each having apertures therein, and a cover comprising sections which overlap the joints in said lid, and which include counter sinks 10 for receiving said ribs.
2. A vault characterized by being made of a composition of enamel and cement and comprising, a sectional base, sectional sides,

sectional ends, a sectional lid, and a sectional cover, the side sections having portions which fit in recesses in the base, each side section having a portion which fits in a recess in said lid, each end section being of angular formation, certain of the end sections having portions which fit respectively in recesses in contiguous side sections and end sections, certain of said end sections having a recess which accommodates a portion of a contiguous end section and a portion which fits in a recess in a contiguous side section, and the cover having recesses therein which accommodate portions on said lid.

In testimony whereof I have affixed my signature.

JOSEPH MANNIX.
